STEAM TRAP

John Thomson, Edinburgh, Scotland

Application October 6, 1947, Serial No. 778,226
In Great Britain June 17, 1947

2 Claims. (Cl. 137—103)

1

The invention relates to apparatus for the removal or ejection of the water of condensation from steam or air pipes, vessels, receivers, jackets, separators, and steam heating systems, subjected to either high or low pressure steam or air for the generation and transmission of power or for process work and commonly known or designated under the general title of steam traps.

The invention has for its object the elimination of ancillary valves which co-operate with fixed or movable valve seatings. Such valves and valve seatings are subject to rapid wear and tear due to the abrading action of water and steam at high velocity and require frequent attention and renewal if loss of heat or air due to excessive leakage is to be avoided.

The invention is applicable to the water-borne upright open bucket type of steam trap in which the opening or closing of the outlet to discharge the water or other fluid is effected by the relative movement of a movable ported tube concentrically disposed internally within a fixed outer tube contained within a closed vessel having inlet and outlet openings, the vessel being pressure-tight under steam, water or air pressure, and the invention consists in forming the termination of the ported tube at its upper end as an unimpeded outlet of nozzle formation.

According to the present invention the movable ported tube is attached to the open bucket and terminates at its upper or discharge end in an outlet of a geometrically formed tapered or nozzle formation so that the extreme internal diameter of the outlet opening is relatively smaller than the internal diameter of the movable tube and the discharge of fluid is unimpeded. The discharge end of the movable tube is so formed with the object of providing, when the trap is in operation, a powerful and positive downward thrust to the bucket, thereby enabling the fluid content of the bucket to be rapidly discharged. In consequence, owing to the rapid gain of buoyancy by the bucket, a powerful upward reacting thrust is imparted to the bucket and inner tube, which ensures rapid closure to discharge. This rapid unimpeded action and reaction is important in that the liability of the movable member to attain a state of equilibrium before the discharge is completely closed, which would result in a constant leak or dribble being maintained, is avoided.

The invention will be more readily understood by reference to the accompanying drawings in which Figs. 1 and 2 are sectional views representing an example of an upright bucket type of steam trap incorporating my invention.

Fig. 1 is an example of an open upright bucket type of float 2 contained within a water chamber 1. To the bottom of the float or bucket 2 is rigidly attached a brass or gunmetal or other metal

tube 4. This tube 4 slides easily and smoothly without perceptible slackness within an outer brass or gunmetal or other metal tube 3 which is rigidly attached at its upper end to a discharge connection 8 on the body of the chamber 1. The connection 8 constitutes an extension of a discharge or outlet channel 9 for the water content of the trap. The upper end of the inner tube 4 is tapered or otherwise reduced to give it a nozzle formation 6. At a predetermined position on the inner tube, two ports or openings 5 are made diametrically opposite each other (see Fig. 2). These ports or openings 5 may be formed rectangular, circular or otherwise and are of sufficient area to give a free discharge.

The operation is as follows: The trap having been connected at its inlet 10 to the vessel to be drained and at its outlet 11 to the discharge, it is desirable before putting the trap into operation that the water chamber 1 be primed or supplied with water to such a level that the bucket float 2 is waterborne and the ports or openings 5 in the inner tube 4 are sealed by the outer tube 3. Connection is then made with the vessel to be drained and steam and water or condensation admitted into the water chamber 1. The gradual accumulation of water eventually raises the buoyant bucket float to a limiting position (shown in Fig. 1 by the dotted outline of the bucket float 2 and inner tube 4). The accumulation of water in the water chamber 1 continues until the water overflows into the bucket float 2. This addition of weight to the bucket float 2 lessens its buoyancy and it begins to sink until the ports or openings 5 in the inner tube 4 attached to the bucket float 2 become uncovered. A discharge of water immediately occurs. Owing to the nozzle formation 6 of the open discharge end of the inner tube 4, a downward impulse or thrust is imparted to the bucket float 2, thereby enabling greater freedom for the discharge of the water content of the bucket float 2. Consequent on the rapid emptying of the bucket float 2 a positive upward impulse or thrust due to the increase in buoyancy of the bucket float 2 is exerted. This becoming insistent, the bucket float 2 moves upward sharply, closing the ports or openings 5, and further discharge ceases. So long as the trap remains in direct connection with the vessel being drained the operation is automatically repeated. A port 12 may be provided to connect the inlet passage 10 with the upper part of the chamber 1 to equalise the pressure of steam or air above and below the water content of the steam trap and so avoid eruptive ebullition of the water content or "water hammer" when steam or air under pressure is admitted to the chamber 1.

I claim:

1. A steam trap comprising a chamber having an inlet passage discharging into the lower por-

tion of the chamber, a discharge passage leading out from the upper portion of said chamber, an upright bucket float movable in said chamber, a ported tube centrally disposed within and fixed to said float, an outer tube fixed at its upper end to and communicating with said discharge passage, said ported tube being slidable easily and without perceptible slackness in said outer tube and having a port covered and uncovered by the lower end of said outer tube by rising and falling movement of the float, the upper end of the ported tube being open, unimpeded and geometrically formed to an upwardly tapered nozzle formation.

2. A steam trap comprising a chamber having an inlet port at its lower end, a discharge passage opening centrally from the upper end of said chamber, a centrally disposed pendant tube attached at its upper end to said discharge passage, a bucket float disposed within said chamber, an inner tube centrally secured within said float and having a port in its wall uncovered by the lower end of said pendant tube when said float is not waterborne and covered by the lower end of said pendant tube when said float rises above a predetermined level and in which the inner tube has an unimpeded open upper end dis-

charging into said discharge passage and geometrically formed in tapered formation at its upper end, and the discharge passage being conically formed to accommodate the tapered formation of the upper end of the said inner tube.
